DESIGN FOR A COMFORTABLE

Peter Joseph, New York, N. Y.

Application August 3, 1939, Serial No. 86,438

Term of patent 7 years

To all whom it may concern:

Be it known that I, Peter Joseph, a citizen of the United States of America, residing in New York city, in the Borough of Manhattan, county and State of New York, have invented a new, original, and ornamental Design for a Comfortable, of which the following is a specification, reference being had to the accompanying drawing, forming part thereof, wherein

The figure is a plan view of a comfortable showing my new design.

The characteristic feature of my design resides in the combination on the comfortable disclosed of the stitched down pleats and the novelty cordings on the center tier trim as shown.

I claim:

The ornamental design for a comfortable, substantially as shown and described.

PETER JOSEPH.
